CLAIM

The ornamental design for a pipe chuck teeth, as shown and described.

DESCRIPTION

FIG. 1 is a top and front perspective view of a pipe chuck teeth embodying my new design;

FIG. 2 is a bottom and rear perspective view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front elevation view thereof;

FIG. 8 is a rear elevation view thereof; and,

FIG. 9 is a top and front perspective view thereof, in which the exemplary pipe chuck structure is shown as a solid object.

The broken lines in the drawings illustrate features of the pipe chuck teeth and environmental structure of a pipe chuck that forms no part of the claimed design.
